CLAIM

The ornamental design for a diagnostic analyzer, as shown and described.

DESCRIPTION

FIG. 1 is a top plan, front and left side perspective view of a diagnostic analyzer showing our new design;

FIG. 2 is a front elevational view;

FIG. 3 is a left side perspective view;

FIG. 4 is a right side perspective view;

FIG. 5 is a rear elevational view;

FIG. 6 is a top plan view; and

FIG. 7 is a bottom plan view thereof.

The dense stippled shading represents dark translucent material of FIGS. 1 and 2.

FIG. 1

FIG. 4

FIG. 2

FIG. 3

FIG. 6

FIG. 7
